Patented July 23, 1918.

UNITED STATES PATENT OFFICE.

LEO RAMSON, OF LEONIA, NEW JERSEY.

ABRASIVE TOOL.

1,273,184.

Specification of Letters Patent. Patented July 23, 1918.

Application filed March 2, 1917, Serial No. 151,878. Renewed June 8, 1918. Serial No. 290,049.

To all whom it may concern:

Be it known that I, LEO RAMSON, a citizen of the United States, residing at Leonia, county of Bergen, State of New Jersey, have 5 made a certain new and useful Invention in Abrasive Tools, of which the following is a specification.

This invention relates to abrasive tools.

The object of the invention is to provide 10 a tool with an abrasive edge or surface which is simple in structure, efficient in operation and economical of manufacture.

A further object of the invention is to provide a tool of the character described 15 wherein the cutting surfaces will not become clogged, and which can be renewed.

A further object of the invention is to provide an adjustable abrasive edge for a tool of this nature which may be shifted at 20 will to the desired contour.

A further object of the invention is to provide a tool of the class described wherein horizontal adjustment of the abrasive edge may be secured.

25 Further objects of the invention will appear more fully hereinafter.

The invention consists substantially in the construction, combination, location and relative arrangement of parts, all as will be 30 more fully hereinafter set forth, as shown by the accompanying drawing, and finally pointed out in the appended claims.

Referring to the drawing,—

Figure 1 is a view in side elevation of a 35 tool embodying my invention.

Fig. 2 is a top plan view of the same.

Fig. 3 is a bottom plan view of the same.

Fig. 4 is a sectional view taken on the line 40 4—4 Fig. 2 and looking in the direction of the arrows.

Fig. 5 is a sectional view taken on the line 5—5 Fig. 4 and looking in the direction of the arrows.

The same part is designated by the same 45 reference numeral wherever it occurs throughout the several views.

In the use of rasps, files, or abrasive tools of like nature for metal or woodwork, various disadvantages have been met with in 50 the art, chief among which are:—

First:—The filings become clogged in the space between the rough edges of the tool. This is particularly true in the case of files. Further, after a file or rasp or other abrasive tool heretofore used has become worn, due to use or any other reason, the file or

rasp becomes useless and requires the purchase of a new tool. Furthermore, the cutting or abrasive edge of the tool always remains the same in contour, and consequently 60 to secure the various shapes required in work of this nature, a number of tools of varying contours is required.

It is among the special purposes of my present invention to provide an abrasive 65 tool, the cutting or abrasive edge of which will not become clogged due to use or wear, and can be readily replaced in standard form and sizes and to provide means associated therewith, to allow the cutting or 70 abrasive edge of the tool to be adjusted from concave to convex at will. Referring to the drawing as illustrating one embodiment of my invention, I provide a base 1, provided with an end portion 2 adapted to receive a handle 3. This may be attached in many ways, but I show a simple way wherein the handle 3 is screwed into the end of the portion 2 of the base or holder 1. The base 1 is provided along one edge thereof with a 75 plurality of lugs 4 formed integral therewith, and the base 1 at the portions thereof at which the lugs 4 are located, is provided with a semi-circular channel indicated at 5. Passing through the channel 5 are bolts 6 80 provided with a lug head 7 at one end thereof, and the other end thereof being adapted to receive a thumb nut 8. Between the lug 4 of the holder 1 and the lug head 7 of the bolt 6 at the respective ends of the holder 1, 85 and suspended by a rotatable pin extending therebetween, I provide a plurality of blades indicated at 10. These blades may be of any structure or material for the purposes required of the tool, but I find hacksaw blades 90 to be efficient, cheap, and satisfactory for this purpose. These hacksaw blades are provided with the usual saw teeth, and are suspended between the pins 9 in substantially parallel 95 relation to each other with their abrasive edge extending downwardly relative to the holder as shown best in Fig. 1. The blades abut on one side against the lugs 4 of the holder, and on the other side against the lug head 7 of the bolt 6, and are held clamped 100 in position by the thumb nut 8.

It is obvious that any size or number of cutting blades may be employed and my invention is not to be limited to such details as size, number, type, and material of the 105 blades or abrasive elements employed.

In normal condition the blades are of the

same height and form a flat abrasive edge for the tool. It is among the purposes of my invention however, to provide means for changing the cutting contour of the tool from extreme convex to extreme concave, and to all intermediary shapes. I show one simple way of accomplishing this wherein the pins 9 which suspend the blades 10 between the ends of the holder 1 are bent or 5 eccentric as seen in Figs. 5 and 3. One end of the pins 10 is provided with a square head 11 to allow the said pin to be rotated. It will be seen that by rotating either one or both of the pins 10, the blades may be adjusted vertically relative to each other to a great number of shapes ranging from extreme concave, slight concave, to slight convex and extreme convex. This is a very desirable feature in tools of this nature in that, with but a single 10 tool an adjustment is secured which allows the same tool to be used, where heretofore a number of tools have been required.

As heretofore stated it is among the objects of my invention to provide means of preventing the cutting surface of the tool from becoming clogged by the material being worked on. In the embodiment of my invention shown, I accomplish this by suitably spacing the blades 10 from each other 15 thereby allowing a space between each pair of blades through which the filings may pass without clogging the cutting edge of the tool. I accomplish this result by inserting what I may term spacing lugs between the respective blades. These spacing lugs 20 may be placed anywhere throughout the length of the tool, but I find it convenient to place the same at one or more of the clamping bolts, according to the particular 25 adjustment required. For example, when it is desired to space the blades 10 on the pins 9, I provide rings 12, see Fig. 4, which I mount on said pins in the desired number between the respective blades according to 30 the space required or desired. If desired or required, spacing lugs 13 may also be provided in any desired number or size between the respective blades at the portions 35 thereof held to the body 1 by the clamps 40 composed of the bolt and thumb nut 6 and 8 and the lugs 4. Thus it will be seen that I provide means for the horizontal adjustment 45 of the blades and this prevents the piece or material being worked on becoming scarred 50 due to continual scraping thereon by the spaced abrasive blades of the tool, by allowing said blades to be bulged at their centers 55 relative to each other to present a longitudinally curved cutting edge rather than a 60 straight line cutting edge as will be readily understood by those skilled in the art.

Another simple way of bulging the blades and to thereby prevent "grooved work" and also to enable the work to be finished up to

a close edge the thumb nut 8 in the center 65 portion of the body 1 may be loosened, and the bolts 6 may be turned out of abutting relation with the end blade or blades 10, and these blades bulged outwardly to allow the lug head 7 of the bolts to be inserted there 70 under, and the thumb nuts again turned to clamp the blades in place, in their distorted position.

I also provide means for locking the pins 11 in their various adjusted positions. While 75 this may be accomplished in many ways, I show one arrangement wherein I provide what I may term a locking lug 14 provided with an aperture at the end thereof, adapted to fit over the square head 11 of the pin 9. 80 These lugs 14 are carried by the bolts 6 at the respective ends of the holder 1 and are clamped into locked position relative to the square head 11 of the pins 9 by means of 85 the thumb nuts 8.

To facilitate the handling of the tool in operation, I provide an auxiliary handle illustrated at 16, which may be of any size, shape or material. In practice, I prefer to curve this handle as shown at 17 to accommodate the thumb of the operator. In the forms shown the auxiliary handle 16 is mounted upon, and secured to the body 1 by a screw 18 to permit a swivel movement of the handle thereon. To accommodate the 90 auxiliary handle 16 the base 1 may be built up as shown in 2 pieces suitably secured together, for example, by solder. My invention is not to be limited to any particular type or form of auxiliary handle, as the 95 same may be dispensed with entirely if desired.

While I have shown and described in detail a specific structure embodying my invention, I wish it to be understood that 105 my invention as defined in the claims is not to be limited or restricted to any specific detail as to structure thereof, as many changes will readily occur to those skilled in the art. Therefore, what I claim is new and useful 110 and of my own invention, and desire to secure by Letters Patent is,—

1. An abrasive hand tool comprising a holder, a plurality of abrasive elements carried by said holder, means for adjusting said 115 element vertically relative to each other to vary the contour of said tool from concave to convex and a handle for said tool.

2. An abrasive hand tool comprising a holder, a plurality of abrasive elements carried by said holder, and means for adjusting 120 said elements horizontally relative to each other and a handle for said tool.

3. An abrasive hand tool comprising a holder, a plurality of abrasive elements carried by said holder and means for adjusting 125 said elements vertically relative to each other to vary the contour of said tool from

- concave to convex, and means for varying the space between said elements and a handle for said tool.
4. An abrasive hand tool comprising a holder, a plurality of abrasive elements carried by said holder, and means for adjusting said elements vertically relative to each other to vary the contour of said tool from concave to convex and means for varying the space between said elements at various points throughout their length, and a handle for said tool.
10. An abrasive hand tool comprising a holder, a plurality of abrasive elements carried by said holder, and means for adjusting said elements vertically relative to each other to vary the contour of said tool from concave to convex and means for varying the space between said elements at various points throughout their length, and a handle for said tool.
15. An abrasive hand tool comprising a holder, a plurality of blades each provided with an abrasive edge, means for securing said blades to said holder and means for shifting the position of said securing means to change the cutting contour of said tool from concave to convex and a handle for said tool.
20. An abrasive hand tool comprising a holder, a plurality of blades each provided with an abrasive edge means including eccentric pins upon which said blades are mounted for securing said blades to said holder, and means for rotating said pins.
25. An abrasive tool comprising a holder, a plurality of blades each provided with an abrasive edge means including eccentric pins upon which said blades are mounted for securing said blades to said holder, and means for rotating said pins, and means for locking said pins in position.
30. An abrasive tool comprising a holder, a plurality of blades each provided with an abrasive edge means including eccentric pins upon which said blades are mounted for securing said blades to said holder, and means for rotating said pins, and means for locking said pins in position.
35. The combination with a plurality of blades and a holder, a handle for said holder, of means for securing said blades to said holder comprising clamping devices, and means carried by said clamping devices for variably adjusting the space between said blades.
40. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and adjustable means for clamping said elements against said lugs.
45. An abrasive hand tool comprising an abrasive surface, and means for varying at will the contour of said abrasive surface from extreme concave to extreme convex or intermediate contours and a handle for said tool.
50. An abrasive hand tool comprising a holder, a plurality of abrasive elements carried by said holder, and means for adjusting said elements vertically relative to each other to vary the contour of said tool from concave to convex, and a removable handle for said holder.
55. An abrasive hand tool comprising a holder, a handle for said holder, a plurality of abrasive elements carried by said holder, and means for adjusting said elements vertically relative to each other to vary the contour of said tool from concave to convex, and a removable handle for said holder.
60. An abrasive hand tool comprising a holder, a handle for said holder, a plurality of abrasive elements carried by said holder, and means for adjusting said elements vertically relative to each other to vary the contour of said tool from concave to convex, and a removable handle for said holder.
65. An abrasive hand tool comprising a holder, a handle for said holder, a plurality of abrasive elements carried by said holder, and means for adjusting said elements vertically relative to each other to vary the contour of said tool, a removable handle for said holder, and an auxiliary handle carried thereby.
70. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and removable bolts provided with a thumb nut for clamping said elements against said lugs.
75. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and removable bolts provided with a thumb nut for clamping said elements against said lugs.
80. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and removable bolts provided with a thumb nut for clamping said elements against said lugs.
85. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and removable bolts provided with a thumb nut for clamping said elements against said lugs.
90. In a tool of the class described, the combination with a holder provided with off set pins at its respective ends, and with side lugs intermediate its ends, of a plurality of substantially parallel abrasive elements carried by said pins to extend substantially the length of said holder, the outer of said plurality of elements abutting against said lugs, and removable bolts provided with a thumb nut for clamping said elements against said lugs.
95. In testimony whereof I have hereunto set my hand on this 26th day of February, A. D., 1917.

LEO RAMSON.
